O. T. SWEET

SAFETY SWITCH

Original Filed Feb. 17, 1919

Inventor
Oliver T. Sweet

By F. R. Cornwall, Atty.

UNITED STATES PATENT OFFICE.

OLIVER T. SWEET, OF ST. LOUIS, MISSOURI.

SAFETY SWITCH.

Original application filed February 17, 1919, Serial No. 277,421. Divided and this application filed May 6, 1921. Serial No. 467,478.

To all whom it may concern:

Be it known that I, OLIVER T. SWEET, a citizen of the United States, residing at St. Louis, Missouri, have invented a certain 5 new and useful Improvement in Safety Switches, of which the following is a full, clear, and exact description, such as will enable others skilled in the art to which it appertains to make and use the same, reference being had to the accompanying drawings, forming part of this specification.

My invention relates generally to electric switches, and more particularly to switches of the knife-blade type, the present application being a division of an application filed by me February 17, 1919, Serial No. 277,421.

The objects of my invention are, to provide a switch having its contacting members arranged within a housing which is closed on all sides and is provided with closure means movably mounted on the cover of said housing and cooperating with the handle of the switch so that the openings in the cover plate and through which said handle operates are closed at all times by said closure means.

Further objects of my invention are to provide a switch in which the blade is operable to simultaneously break contact with both terminal contacts and is adapted to move away from said contacts the prescribed distance required by the regulations pertaining to the installation of electrical 35 devices in buildings.

Another object of my invention is to provide a switch, the contact establishing parts of which are normally inaccessible so that a person operating the same is protected from 40 electrical discharges and which switch is of simple construction and highly efficient in operation.

In the drawings—

Figure 1 is a perspective view of the 45 switch housing showing the movable closure member mounted thereon.

Figure 2 is a vertical cross section of said switch.

Figure 3 is a transverse vertical cross 50 section taken on line 3—3 of Figure 2.

Figure 4 is a horizontal cross section taken on line 4—4 of Figure 3.

Referring by numerals to the accompanying drawings, 10 represents a housing of 55 porcelain or analogous insulating material,

said housing being preferably of rectangular shape. Arranged in said housing are one or more compartments or recesses 11. The top and bottom of each compartment is provided with openings 14 through which the terminals of the lines enter each compartment 11. Contact plates 15 and 16 are located in each compartment and are designed to be connected to the terminals of the lines by means of screws or like fastening means 17 which are screw-seated in said plates. Contact plate 15 is arranged in the upper portion of each compartment and is supported therein by a screw 18 seated in the rear wall of housing 10 and engaging the lower end of said contact plate. Contact plate 16 is held in the lower portion of each compartment by a screw 19 seated in the rear wall of said housing and having its threaded end engaging the upper end of contact plate 16.

Adjoining contact plate 15 is a U-shaped contact member 20 and adjoining contact plate 16 is a U-shaped contact member 21. These contact members are preferably held in position by screws 18 and 19 so that said contact members are electrically connected to the terminals of the lines through their respective contact plates 15 and 16. The ends of U-shaped contact members 20 and 21 are bent inwardly so as to yieldingly engage the ends of knife-blade 22 which is supported in each compartment by a pair of links 24. These links are pivotally mounted in stationary supports 25 carried by the rear wall of housing 10 and the free ends of said links are pivotally connected to the switch blade 22.

A handle 26 is arranged exteriorly of said housing and has fingers or projections 28 which project inwardly into each compartment through slots 27 vertically disposed in the cover plate 27 which forms the front wall of said housing. The inner ends of these fingers are connected to corresponding knife-blades 22, there being a projection 28 provided for each knife-blade. Links 24 are preferably of equal length and constitute a parallelogrammatic support for knife-blades 22 whereby when handle 26 is operated, blades 22 are moved outwardly and by virtue of their pivotal mounting on the free ends of links 24, each blade 22 will be equidistant from its corresponding members 20 and 21 so that the circuit is broken 11.

simultaneously at both terminals. Housing 10 is of sufficient depth and links 24 of proper length to permit switch blade 22 to be moved the predetermined distance from 5 contact members 20 and 21.

The upper ends of slots 27^a are united by a horizontally disposed slot or opening 27^b which is of sufficient size to permit the passage of handle 26 therethrough when attaching or detaching cover plate 27 to or 10 from housing 10. A closure plate 29 is slidably mounted on cover 27 by means of vertical guideways 30 removably secured to said cover on each side of plate 29. A horizontally disposed opening 31 is formed in plate 15 29 to accommodate the outwardly projecting handle 27.

When handle 26 is operated to open the circuit, said handle and the switch blades 22 20 are moved downwardly and outwardly to occupy positions shown in dotted lines in Figure 2. The downward movement of handle 26 causes the plate 29 to slide downwardly in guideways 30 so that the upper 25 portion of said plate will be positioned against and close the horizontal opening 27^b and the upper portions of vertical slots 27^a. Plate 29 extends upwardly a sufficient distance to maintain openings 27^a and 27^b 30 closed at all times so that the compartments in which contact members and the switch blades are mounted are rendered inaccessible, thereby eliminating any danger of injury to a person from electrical discharges 35 or fire caused thereby.

The mounting of switch blade 22 by the use of pivotally supported links 24, provides means whereby the switch blade is maintained in position which is parallel with 40 terminal contacts 20 and 21, so that the switch blade 22 engages and disengages both of said terminal contacts simultaneously.

Links 24 do not form part of the electrical circuit and are not connected therewith; consequently when blade 22 is disengaged from contact members 20 and 21 45 all electrical connection between said blade and the electrical circuit ceases and the blade is "dead" or inactive.

50 A switch constructed according to my invention is quick and positive in its action, has few operating parts, and can be safely operated.

I claim:

55 1. In a safety switch construction, the combination of an insulation housing having a plurality of separate compartments, a pair of stationary contact members in each compartment, a pair of links pivotally supported in each compartment, a switch blade pivotally mounted on the free ends of 60 said links and movable into simultaneous engagement with both of said contact members, a closure plate for said housing, said plate being provided with vertically dis-

posed slots, a handle arranged exteriorly of said housing and having fingers projecting inwardly through said slots into said compartments for engaging said blades, and a sliding plate having cooperative engagement with said handle and contacting with said closure plate whereby the slots formed therein are closed at all times.

2. In a safety switch construction, the combination of an insulation housing having 75 a plurality of separate compartments, a pair of stationary contact members in each compartment, a pair of links pivotally supported in each compartment, a switch blade pivotally mounted on the 80 free ends of said links and movable into simultaneous engagement with both of said contact members, a closure plate for said housing, said plate being provided with vertically disposed slots, a handle arranged exteriorly of said housing and having fingers projecting inwardly through said slots into said compartments for engaging said blades, a sliding plate having cooperative engagement with said 85 handle and contacting with said closure plate whereby the slots formed therein are closed at all times, and vertically disposed guides on said closure member for engaging the edges of said sliding plate and guiding it in its movement.

3. In an apparatus of the class described, a switch comprising in combination a housing divided into separate compartments, 100 terminal contact members arranged in each compartment, a switch blade in each compartment cooperating with said contact members, a handle arranged exteriorly of said housing and having fingers projecting into each compartment fixed to each switch blade and movable in vertical plane, pivotal means for movably supporting said switch blade in the housing whereby said switch blade is movable in parallel with the contact members, a cover plate for the housing, 105 said cover plate having vertically disposed openings through which the fingers of said handle operate, and closure means slidably mounted on said cover plate and adapted to move in a vertical plane in co-operation with said handle and close the unoccupied portion of the handle opening.

4. In an apparatus of the class described, the combination of a switch block provided with a recess, there being apertures formed through the body of the block near the ends of said recess, contact members within said recess, attaching devices for securing the wire terminals which extend into said housing through said openings to said contact members, supporting means pivotally mounted in said recess, a switch blade pivotally carried by said supporting means and adapted to establish electrical connection between said contacts, a cover plate of insu- 115 120 125 130

lating material applied to the block over the recess therein, said cover plate being provided with a vertically disposed slot, a handle for operating the switch blade, said handle being located on the exterior of the cover plate and having a portion extending through the slot and secured to the switch blade and closure means for said slot mounted for vertical movement on said

10 cover and movable co-operatively with said handle.

5. In an electric switch the combination of a housing provided with separate compartments, a plurality of contact members arranged in each compartment, a switch blade mounted in each compartment and movable in parallel with said contacts, a cover plate secured to said housing, an operating handle fixed to said blades and projecting outwardly through slots vertically arranged in said plate, guides secured to said plate, and vertically movable closure means slidably mounted in said guides and

co-operating with said handle for closing said slots in said plate.

25

6. In an electric switch, the combination of an insulated housing provided with separate compartments, a pair of stationary contact members arranged in each compartment, a switch blade in each compartment adapted to simultaneously engage and disengage said contact members, a cover plate for said housing provided with vertically disposed slots, an insulation handle arranged outwardly of said plate and having fingers projecting inwardly through said slots and engaging said blades, and a vertically disposed closure member slidably mounted on said cover and having an opening for the accommodation of said handle, whereby said closure member moves in vertical plane on said plate when said handle is operated.
